UNITED STATES PATENT OFFICE.

GEORGE A. MELLON, OF ST. LOUIS, MISSOURI.

SPRING BED-BOTTOM.

1,094,373.

Specification of Letters Patent. Patented Apr. 21, 1914.

Application filed December 15, 1913. Serial No. 806,789.

To all whom it may concern:

Be it known that I, GEORGE A. MELLON, a citizen of the United States of America, and a resident of the city of St. Louis and State of Missouri, have invented certain new and useful Improvements in Spring Bed-Bottoms, of which the following is a full, clear, and exact description, reference being had to the accompanying drawing, forming 10 a part of this specification.

My invention relates to a bed spring, and has for its object the production of a very resilient bed spring adapted to yield throughout its length, and constructed to 15 withstand severe strains without injury to the various spring elements.

Prior to this invention bed springs have come under one of the following classes: First, spiral springs adapted to yield vertically and supported by a rigid base. The usual form of rigid base consists of transverse slats, or non-yielding wires. Second, web springs yieldingly connected to the 20 ends of a rigid frame.

Spiral springs arranged throughout the bed spring structure yield freely and form a cushion for all parts of the body of a person using the bed spring, but when subjected to the weight of an unusually heavy person, the spiral springs are strained beyond their elastic limit, and, owing to the rigid base below the springs, they do not form a comfortable support when compressed beyond certain limits. Therefore these spiral springs 25 are frequently impaired by excessive compression upon the rigid base, and at best their resilience is materially affected by such rigid base. Another objectionable feature found in the spiral compression springs as ordinarily used is that the spring structure must fit onto a rigid base which lies wholly between the side rails of the bed, and such spring structures are often a misfit on account of the many variations in the distance 30 between the side rails of different beds.

Web springs having their ends secured to a rigid frame may be made interchangeable to fit beds made by different manufacturers, but springs of this kind are not of uniform resilience throughout the surface of the bed. The middle portion of the web may yield freely and possess the desired resilience, but the ends of the web are more rigid and no appreciable resilience is present below the head and shoulders of the user.

The preferred form of my invention com-

prises a rigid frame adapted to fit any standard bed, a flexible frame yieldingly connected to said rigid frame, compression springs supported by said flexible frame, and a second flexible frame connecting the upper ends of said compression springs. The compression springs are distributed throughout the structure to form a cushion for all parts of the body of the user, and owing to the flexibility of the yielding bottom frame, one side of the spring structure may be depressed by the weight of a heavy person without materially distorting the other side of the spring structure. It will also be noted that the yielding lower frame serves to relieve the spiral compression springs of excessive strains, which would be present if the spiral springs were supported by a non-yielding base.

My invention is also to be distinguished from an old spring structure which consists of a rigid frame having end rails, a spring web stretched from end rail to end rail and lying flush therewith, spiral springs below 35 the middle of said stretched web, and truss-like wires supporting said spiral springs, the ends of said truss-like wires being attached to the end rails. The resilience of a spring of this kind is mainly in the stretched web and the middle of this web is reinforced by spiral springs resting on a non-yielding support. The head and shoulders of the user are not cushioned by the spiral springs at the middle of the bed.

Figure I is a side elevation, partly broken away, of a bed spring embodying the features of my invention. Fig. II is a horizontal section taken approximately on the line II-II, Fig. I, showing the yielding frame that supports the compression springs.

In the accompanying drawings: A designates a rigid frame comprising end rails 1, side rails 2, below said end rails, and connecting members 3, connecting the end rails 100 to the side rails. The connecting members 3 are preferably provided with arms 4 adapted to rest upon the side rails of a bed.

The spring elements comprise spiral compression springs 5 arranged between and secured to flexible frames B and C, and tension springs 6 connecting the ends of the flexible frame C to the end rails 1. The flexible upper frame B may be of any suitable construction but the flexible lower frame C preferably consists of transverse wires 7 and longitudinal wires 8 interlaced

with said transverse wires. The compression springs 5 are secured to the flexible bottom frame at the junctions of the wires 7 and 8, and the ends of the longitudinal wires 8 are connected to the end rails by the tension springs 6. The flexible web formed by the wires 7 and 8 is held under tension by the tension springs 6, so that said flexible web lies flush with the rigid end rails 1, and the flexible top frame or web B, having no direct connection with the rigid frame, is free to yield at all points throughout the structure. When the spiral springs 5 are subjected to excessive pressure, the strains are transmitted through the wires 8 to the tension springs 6, so as to relieve the springs 5 of strains that would impair their inherent elasticity, thereby preventing injury to the springs 5 and at the same time providing an auxiliary cushioning device for unusually heavy persons.

I claim:—

1. The combination in a bed bottom, of a rigid frame including end rails, lower and upper pliable frames, the said lower frame being connected to the end rails of said rigid frame and free of connection with the side of said rigid frame, and compression springs between said pliable frames.
2. The combination in a bed bottom, of a rigid frame including end rails, a main spring structure comprising lower and upper pliable frames and compression springs between said pliable frames, and tension springs connecting said lower pliable frame to the end rails only of said rigid frame.
3. The combination in a bed bottom, of a rigid frame including end rails, and a spring structure comprising pliable lower

and upper frames, and compression springs between said frames, the said lower frame including longitudinal wires and transverse wires, the longitudinal wires having connection with the end rails of said rigid frame and the transverse wires being free of direct connection with said rigid frame.

4. A bed bottom comprising a rigid frame, a pair of pliable frames arranged one above the other, tension springs connecting the lower pliable frame to said rigid frame, and compression springs between said pliable frames, the upper pliable frame having no direct connection with said rigid frame, the said upper pliable frame being supported wholly by said compression springs.

5. A bed bottom comprising a rigid frame having end rails, a pliable lower frame in the form of a wire web extending substantially from end to end of said rigid frame, tension springs connecting the ends of said wire web to said end rails and thereby holding said web, under tension, at the level of said end rails, compression springs on said wire web, and a pliable upper frame secured to said compression springs.

6. A bed bottom comprising a rigid frame, a pliable upper frame, a pliable lower frame consisting of longitudinal and transverse wires, tension springs connecting said longitudinal wires to said rigid frame, and compression springs arranged between said pliable upper and lower frames and secured to the said pliable lower frame at the junction of said longitudinal and transverse wires.

GEORGE A. MELLON.
